FUEL FEEDING DEVICE

Filed Oct. 20, 1928

Fig. 1

UNITED STATES PATENT OFFICE

CHARLES S. BURTON, OF OAK PARK, ILLINOIS

FUEL-FEEDING DEVICE

Application filed October 20, 1928. Serial No. 313,703.

The purpose of this invention is to provide an improved apparatus for lifting liquid, particularly adapted for lifting fuel from a lower source to a receptacle suitably located for supplying the carburetor of an internal combustion engine, and also particularly adapted to employing suction derived from the intake manifold of the engine served.

10 It consists in the elements and features of construction herein shown and described as indicated in the claims.

In the drawings:

Figure 1 is a vertical section of a vacuum tank embodying this invention substantially axial with respect to the concentric chambers.

Figure 2 is a fragmentary detail plan view of the top of the tank shown in Figure 1, for showing in detail the construction of atmosphere inlet and valve.

Figure 3 is a detail section at the line 3-3 on Figure 2 upon an enlarged scale.

Figure 4 is a fragmentary portion of Figure 2 upon an enlarged scale.

It is well understood by those familiar with the operation of fuel supply devices of the character commonly called "vacuum tanks", that a problem is presented by the fact that the atmosphere inlet valve, being held to its seat by suction derived from the engine intake manifold while the suction valve is open, being opened by the buoyant effort of the float due to its becoming submerged by the rise of liquid in the vacuum chamber drawn into it by the suction, is limited as to the area for pressure holding it seated, to that on which the excess of atmosphere pressure existing in the chamber under the maximum suction will not exceed the buoyant value of the float then submerged at the high liquid level; or as it is commonly expressed, that the float must be large enough to break the suction hold of the atmosphere valve by its buoyancy when the vacuum chamber is filled to high level.

This limitation on the size of the atmosphere valve is a limitation upon the capacity 50 of the tank of a given size for supplying

fuel to the engine, because the size of the atmosphere inlet port and valve affects the length of time required for relieving the vacuum after the atmosphere valve opens so that the liquid can be discharged from the vacuum chamber into the reserve chamber. And also the size of the atmosphere port and valve affects the rate at which the liquid can be discharged after the vacuum is relieved. And especially if the suction 55 valve is omitted, the size of the atmosphere port and valve must be so many times larger than the suction port in order that when the atmosphere valve opens, the vacuum in the chamber shall be reduced to a lower degree than that which will uphold a liquid column as high as the entire depth of the chamber from the discharge valve to high liquid level, since the discharge will only lower the level to that height.

The leading purpose of the present invention is to avoid the difficulty above indicated which arises from the fact that the atmosphere valve is positioned for being stressed on its seat by the suction, this avoidance being accomplished by arranging the atmosphere valve so that the action of the suction upon it is to the contrary of stressing upon its seat, said valve being positioned interiorly with respect to the vacuum chamber and stressed upon its seat by spring means, the spring being in condition for reacting to thus stress the valve with pressure not exceeding the maximum suction which is operative in the chamber with the suction valve open for lifting the fuel into the chamber, this maximum suction being that which results from the degree of vacuum induced in the chamber by connection with the engine intake manifold and which accordingly can never exceed and for operating the tank must be measured by hydrostatic pressure of the fuel column from the fuel source to the fuel inlet in the chamber.

Under these conditions the atmosphere 95 valve is held seated by the spring while the suction connection is open for producing partial vacuum in the chamber and while the chamber is accordingly filling by fuel lifted from the lower source; and connection being 100

provided by which the float rising with the rise of the liquid level in the chamber may actuate the atmosphere inlet valve in direction for opening.

This actuation is effected easily and with certainty by the buoyant value of the partly submerged float because said valve is substantially balanced on its seat, the spring pressure being opposed by the suction and the spring being tensioned to the suction resulting from the partial vacuum in the chamber which is unvarying except as the vehicle on which the engine served is mounted may be traveling on an incline either upwardly or downwardly so that the distance which the fuel must be lifted varies to the extent of the difference between the level of the fuel tank in climbing and descending the grade.

In the preferred construction the atmosphere valve is mounted for sliding on its seat to open and close so that the resistance to its opening is merely the friction on its seat which is substantially zero under the condition as to inclination of the vehicle to the grade for which the spring is adjusted and the condition which arises in ascending the grade making the suction lift more than that for which the spring is adjusted so that the stress exerted by the spring on the valve is less than the suction; the only case in which there will remain any friction between the valve and its seat due to pressure of the valve on the seat being the condition of descending the grade in which the suction is slightly less than that for which the spring is adjusted. Although the sliding valve construction is preferred, the principle of the invention is applicable to a construction in which the valve is opened and closed by movement from and toward its seat instead of sliding on it.

Referring to the drawings:—

The main or outer body member forming the lower or reserve fuel chamber is shown at A, and the member which forms the vacuum chamber is shown at B. The two members are secured together by an annular coupling member, C, zig-zag in form, in radial section to facilitate its securement by its inner circumferential margin to the upper end of the vacuum chamber member, B, which has at said upper end an outwardly turned horizontal flange, 20, lapping and secured air-tight, as by soldering, onto the inner circumferential horizontal flange, 25, of the coupling member, C, whose outer circumferential flange, 21, which is vertical, is lapped outside the upper end of the body member, A, and may be soldered thereto. The member, C, thus constitutes the upper end closure of the annular passage cavity, c, formed between the outer member, A, and the vacuum chamber member, B.

The vacuum chamber member is closed at the top by a cap, D, which has a downwardly folded peripheral flange, 30, dimensioned for

encompassing and fitting snugly about the intermediate vertical shoulder, 23, of the zig-zag coupling member, C. The cap, D, is arranged to be secured in place for closing the vacuum chamber and also extending over the annular area of the horizontal flange, 25, which, as mentioned, closes the upper end of the annular space, c, by screws, 31, set through the cap just inside the peripheral flange, 30, and screwed into the horizontal flange, 25, above which, as mentioned, the flange, 20, of the vacuum chamber member, B, is lapped, said last mentioned flange having apertures registering with the threaded holes in the flange, 30; and a packing gasket, 27, is interposed over said flange so that when the screws, 31, are set, the vacuum chamber is sealed at the top except as to atmosphere, suction, and fuel inlet hereinafter described, said sealing being both as against outer atmospheric pressure and air communication between the vacuum chamber and the annular space, c, and thereby with the remainder of the fuel reserve chamber.

This construction, it may be observed, facilitates mounting all the movable parts concerned in the atmosphere, suction and fuel communications with the vacuum chamber on the cap plate within the area thereof which overlies the vacuum chamber, so that for any attention which these parts may require or may desirably receive in the service of the apparatus may be readily obtained by withdrawing the screws and removing the cap, withdrawing it from the vacuum chamber, carrying every part which might require any sort of attention or replacement.

The cap, D, has accordingly a fuel inlet pipe fitting, 40, mounted liquid-tight, preferably at a point near the circumference where said fitting projects inwardly, terminating for discharge of the fuel close alongside the outer wall of the vacuum chamber. At a point conveniently remote from the fuel inlet fitting, 40, there is mounted in the cap a suction connection fitting, 50, having a very restricted port, 51, for access of suction,—outflow of air or gas to the source of suction,—which may be the intake manifold of the engine served according to familiar fuel feeding methods, an elbow, 51^a, being attached to the exteriorly protruding end of the fitting, 50, for connection in any convenient manner with a pipe leading to the source of suction.

For the atmosphere inlet there is provided a valve seat plate, F, applied with interposed packing gaskets, 45, on the top side of the web of the cap, D, said web having an oblong aperture, 55, less in both horizontal dimensions than the plate, F, which accordingly laps the margin of said aperture, 55, on all four sides, so that when the valve seat plate is secured tightly with the gasket, 45, intervening there is no air leak at the joint between it

and the web of the cap, D. This plate being designed to form the valve seat as mentioned for the atmosphere valve, G, which is a flat plate dimensioned for fitting slidingly in the aperture, 55, which the valve seat plate, F, covers, said valve plate being enough less in its longitudinal dimension than said aperture so that it may have a range of sliding movement in the aperture for opening and closing 10 the atmosphere inlet ports, as will now be described.

The valve seat plate, F, has a plurality of narrow preferably parallel slots, 60, extending cross-wise of the slot, 55, and of the plate, 15 F; and the valve, G, is similarly formed with a like plurality of similar slots, 70, similarly spaced and arranged, so that the valve may be positioned on the valve seat plate with the apertures of the valve registered with those 20 of the valve seat plate, and by longitudinal movement of the valve in the slot, 55, from the position at which the slots, 60 and 70, are registered with each other, a distance slightly more than the width of said equally dimensioned slots, the atmosphere access to the vacuum chamber will be completely cut off.

For upholding the slide valve, G, against the seating plate, F, there is provided a flat spring bar, 80, flexed at one end to form an 30 open loop or 180° return bend as seen at 81, the reflexed end being made fast by riveting or soldering it to the under side of the web of the cap, D, and the free end being arranged to bear upwardly against the under side of the 35 valve, G, and to be stressed thereagainst to a predetermined pressure by an adjusting screw, 65, which is inserted upwardly through a hole in the spring bar, 80, near the return bend, and screwed through a boss, 83, made fast on the web of the cap, the head of the 40 screw being stopped on the under side of the spring bar, 80, the exteriorly protruding end having a slot, 66, for engagement by a screw driver to adjust the screw for the predetermined degree of stress with which the valve 45 is held to the seat.

For operating the atmospheric valve, G, a bell crank lever, H, is fulcrumed at 71 in the bracket, 72, depending rigidly from the web of the cap, D; and from the horizontal arm, h, of the bell crank lever there is pivotally suspended a float-guide-rod, J, having stops, 73 and 74, spaced apart on the rod a substantial distance more than the vertical dimension 55 of the float, K, which is mounted slidingly on the rod between said stops. The float-guide-rod is positioned at its lower end by extending through an aperture at the center of the spider, 91, formed at the upper end of the discharge fitting, 90, which carries at its lower 60 end in the fuel reserve chamber the usual discharge check valve, 92.

The horizontal arm, h, of the lever, H, is threaded beyond the pivotal connection of the rod, J, to receive a weight, M, which is

thereby made adjustable along the lever arm for a purpose which will be explained.

From the foregoing description it may be understood that when the tank is connected for deriving vacuum from the source of 70 vacuum, as the intake manifold of the engine served, and is connected for receiving fuel by the fuel inlet, 40, connected with the low level fuel supply tank, both chambers of the device being empty and the atmosphere valve 75 being closed by the float lodged upon the lower stop, 74, of the float-guide-rod, and operating by its weight added to the weight of the horizontal arm of the bell crank lever for holding the atmosphere valve, G, at closed 80 position, as seen in Figure 1, fuel will be drawn by suction from the low level supply into the vacuum chamber, eventually causing the float to be lifted along the float-guide-rod into contact with the upper stop, 73, with 85 the tendency, by buoyant action of the float, to raise the horizontal arm of the bell crank lever, causing the vertical arm to operate the atmosphere valve, sliding it from position at which the ports are closed to position of 90 registration of the ports, 70, of the valve with the ports, 60, of the valve seat, thereby admitting atmosphere freely by reason of the relatively large aggregate area of the plurality of ports of the valve and seat. 95

By reason of the large ration of the atmosphere inlet ports to the very small area of the restriction, 51, in the suction fitting, 50, by which the suction has access to the vacuum chamber, the opening of the atmosphere valve, as described, results in a condition closely approximating atmospheric pressure in the vacuum chamber, causing the delivery of the fuel from the vacuum chamber into the reserve chamber, and the lowering of the 100 float until it lodges upon the lower stop, 74, and by its weight operates the bell crank lever for closing the atmosphere valve, whereupon the continued access of suction reproduces a condition of partial vacuum in the vacuum 105 chamber, causing the cycle of the operation to 110 be repeated.

A distinguishing characteristic of the construction and operation is that the atmosphere valve being held to its seat by the spring, H, 115 is so held against the excess of atmospheric pressure over the sub-atmospheric pressure existing in the vacuum chamber when the atmosphere valve is closed by reason of the continuously open suction connection. And the degree of vacuum in the vacuum chamber resulting from the continuous access of suction is limited and measured by the fuel lift and can in no case exceed the degree of 120 vacuum necessary to lift the fuel from the fuel source to the point of discharge in the vacuum chamber so long as such flow of the fuel is free. In any given installation on a motor vehicle this lift is fixed by the installation of the vacuum tank and fuel source re- 125 130

spectively, subject to variation according to the grade upon which the vehicle is moving, the lift being greater when the vehicle is traveling up-grade and less when it is traveling down-grade. The tension of the spring, 5 H, being adjusted for holding the valve to its seat against the suction operating in the vacuum chamber when the vacuum is maximum, that is, when the vehicle is advancing 10 on a maximum grade, the atmosphere valve will remain closed and cause the development of vacuum in the vacuum chamber to the degree necessary for lifting the fuel from the main tank to the vacuum chamber under all 15 conditions. And the valve will be held to its seat frictionally as against the sliding movement necessary for opening only by the excess of the spring pressure, which is adjusted to the maximum suction, over the actual suction 20 which will be less than maximum when the vehicle is standing or moving on the level, or ascending less than the maximum grade or on a descending grade.

Under these conditions the buoyant or gravity effort of the float and connections necessary for giving the atmosphere valve either 25 opening or closing movement is relatively small, and the movement necessary for opening and closing being very short, the delay in the opening movement, for example, when 30 the float is being lifted by the accumulation of liquid in the vacuum chamber after the float strikes the upper stop, is sufficient so that the increase in submergence of the float which 35 will occur before the buoyant value of the float becomes sufficient to break the valve from its seat against the friction hold will ensure the completion of the opening movement by inertia and the upward movement of 40 the float for reaching the condition of balance in the liquid.

Similarly, in the emptying of the vacuum chamber which follows the opening of the atmosphere valve, the valve being held to its 45 seat by the full force of the spring, suction being practically absent by reason of the atmosphere valve ports being wide open, when the float descending encounters the lower stop it will be arrested by that stop 50 while the liquid level continues to descend; and when the float is completely de-submerged, the liquid level having fallen below its lower end if the weight of the float and the lever are made sufficient to break the 55 friction hold of the valve on its seat, which is caused by the stress of the spring, the valve will start to move in closing direction, and the movement being very short will be completed by inertia and the continued gravity 60 action of the float and connections before the float descends into the liquid sufficiently to defeat the action, especially in view of the fact that the liquid level is also descending while the valve movement is occurring.

55 The purpose of the weight, M, mounted

adjustably on the horizontal arm of the lever, is to provide for accurate adjustment compensating for any unavoidable variation in the weight of the float and connections to ensure that the weight is sufficient for closing 70 the valve against the friction hold as described.

Upon consideration of the structure it may be understood that if from any cause, as obstruction to the inflow of fuel from the low 75 fuel source while the atmosphere valve is at closed position, the vacuum developed in the vacuum chamber should exceed that by which the spring, 80, is adjusted, the atmosphere valve being thus eased on its seat, admitting 80 air without making its sliding opening movement will cause the vacuum to be vented, thereby governing the maximum vacuum effective in the chamber.

The valve seat plate, F, and valve, G, are 85 desirably made of rust-proof material, as of bronze, to insure against the two parts becoming adherent or roughened by rust during 90 intervals of idleness which would prevent the free sliding movement of the valve.

I claim:—

1. In a structure for the purpose indicated in combination with a chamber arranged to be connected with a source of suction for producing partial vacuum in said chamber and having a liquid supply connection and an atmosphere inlet port, an inwardly opening valve which controls the atmosphere inlet port arranged also for sliding on its seat for opening and closing, and having associated with it a spring stressing it on its seat adapted to yield to permit the valve to be eased on its seat by the suction for venting the vacuum in the chamber upon the vacuum passing a predetermined degree, a float in the chamber and means positioned for being actuated by the float at a predetermined high level of the liquid in the chamber, and operating connections from said means for giving the valve sliding opening movement.

2. In a structure for the purpose indicated in combination with a chamber arranged to be connected with a source of suction for producing partial vacuum in said chamber and having a liquid supply connection, and an atmosphere inlet port, an inwardly opening valve which controls the atmosphere inlet port arranged also for sliding on its seat for opening and closing, and having associated with it a spring stressing it on its seat, adapted to yield to permit the valve to be eased on its seat by the suction for venting the vacuum in the chamber upon the vacuum passing a predetermined degree, a float in the chamber and means positioned for being actuated by the float at a predetermined low level of liquid in the chamber, and operating connections from said means for giving the valve sliding closing movement.

3. In a construction for the purpose indi-

cated in combination with a chamber connected with a source of suction for producing partial vacuum in the chamber, and having an atmosphere inlet port, a valve seated interiorly of the chamber controlling said port, mounted for sliding on its seat for opening and closing; a spring conditioned for reacting on the valve to stress it upon its seat against a predetermined degree of opposite pressure, whereby upon the vacuum in the chamber, causing the excess of atmospheric pressure at the inlet port to reach said degree the valve ceases to press frictionally on its seat, and means in the chamber operated by change of level of the liquid therein for sliding the valve for opening and closing at predetermined high and low levels respectively.

4. In a construction for the purpose indicated, a chamber having connection with a source of suction and with a source of liquid to be lifted by the suction, and having an atmospheric inlet, a valve controlling said inlet, and means in the chamber arranged to be operated by change of level of the liquid therein for opening and closing the atmosphere inlet controlling valve at predetermined high and low levels respectively of the liquid, the valve being arranged for sliding on its seat for opening and closing, the valve seat having a plurality of oblong apertures very narrow relatively to their length arranged in parallel lengthwise, forming the atmosphere inlet port, the valve being similarly formed with apertures arranged for registering with those of the seat at open position of the valve, the opening and closing movement of the valve being transversely of the direction of parallelism of said apertures.

5. In a construction for the purpose indicated, a chamber having connection with a source of suction and with a source of liquid to be lifted by the suction, and having an atmospheric inlet, a valve controlling said inlet, and means in the chamber arranged to be operated by change of level of the liquid therein for opening and closing the atmosphere inlet controlling valve at predetermined high and low levels respectively of the liquid, the valve being arranged for sliding on its seat for opening and closing, the valve seat having a plurality of apertures each very narrow relatively to its length, said apertures extending lengthwise transversely to the direction of said sliding movement forming the atmosphere inlet port, the valve being similarly formed with apertures arranged to register with those of the seat at the open position of the valve.

6. In the construction defined in claim 1, the atmosphere port being in the top of the vacuum chamber at a substantially horizontal part thereof, whereby the valve seating at the under side of the seat tends by gravity

to leave the seat and admit atmosphere and ease the friction of its sliding movement.

7. In the construction defined in claim 1, the atmosphere port being in the top of the vacuum chamber at a substantially horizontal part thereof, whereby the valve seating at the under side of the seat tends by gravity to leave the seat and admit atmosphere and ease the friction of its sliding movement, the operating connections for actuating the valve for opening and closing consisting of a bell crank lever having a substantially upstanding arm arranged to engage the valve, and a substantially horizontal arm for actuation by the float.

8. In the construction defined in claim 1, the atmosphere valve seat being provided by a plate secured on the outside of the vacuum chamber, the chamber wall having an aperture closed by said seat, plate and an atmosphere valve, being a plate dimensioned for fitting slidingly in said aperture; whereby the edges of the aperture serve as guideways for the valve in its opening and closing movements.

9. The construction defined in claim 5, the atmosphere valve seat being provided by a plate applied on the outside of the vacuum chamber, the wall of the chamber having an aperture which is closed by the plate, and a valve being dimensioned for fitting slidingly in said aperture with its vent apertures registering with those of the valve seat plate.

10. The construction defined in claim 5, the atmosphere valve being provided by a plate applied on the outer side of a substantially horizontal part of the wall of said chamber, said wall having an aperture which is closed by said valve seat plate, and the valve being a plate dimensioned for sliding fit in said aperture.

11. The construction defined in claim 5, the atmosphere valve being provided by a plate applied on the outer side of a substantially horizontal part of the wall of said chamber, said wall having an aperture which is closed by said valve seat plate, and the valve being a plate dimensioned for sliding fit in said aperture, the operating connections for actuating the valve for opening and closing consisting of the bell crank lever having a substantially upstanding arm arranged to engage the valve and a substantially horizontal arm for actuation by the float.

12. The construction defined in claim 1, the operating connections for giving the valve its sliding movement comprising a substantially horizontal lever arm having a weight adjustable longitudinally of said arm for varying the gravity forces in opposition to which the buoyancy of the float operates to open the valve.

13. The construction defined in claim 2, the operating connections for giving the valve

its sliding movement comprising a substantially horizontal lever arm having a weight adjustable longitudinally thereof for varying the gravity forces operative for giving the valve its closing movement against the friction due to the reaction of the spring pressing it on its seat.
